UNITED STATES PATENT OFFICE.

EUGENE ORA DANIELS, OF TOLEDO, OHIO.

HEATING STOVE.

Application filed June 28, 1917. Serial No. 177,514.

To all whom it may concern:

Be it known that I, EUGENE O. DANIELS, a citizen of the United States, residing at Toledo, in the county of Lucas and State 5 of Ohio, have invented certain new and useful improvements in Heating Stoves, of which the following is a specification, reference being had therein to the accompanying drawing.

10 This invention relates to certain new and useful improvements in heating stoves and more particularly to that class of stoves known in the art as gas or vapor stoves, the object being to provide a heating stove 15 which is exceedingly simple and cheap in construction and one in which a large radiating surface is provided for heating the air passing upwardly through the center of the stove.

20 Other and further objects and advantages of the invention will be hereinafter set forth and the novel features thereof defined by the appended claim.

In the accompanying drawings,

25 Figure 1 is a side elevation of my improved construction of heating stove partly in section;

Figure 2 is a section taken on line 2—2 of Fig. 1;

30 Figure 3 is a detail vertical section of the upper portion of the stove showing a slightly modified form; and

Figure 4 is a top plan view of the flue ring.

35 Like numerals of reference refer to like parts in the several figures of the drawing.

In the drawings 1 indicates a circular burner mounted on legs 2 and provided with supply pipes 3 terminating in a centrally disposed casing 4 in which a gas cap 5 is mounted having gas chambers 6 and 7. The gas cap 5 carries a pin 8 seated within notches formed in the casing 4 and a threaded stem 9 on which is mounted a nut 10 for 40 holding the cap in position within the casing 4 as clearly shown in Fig. 1. The notches of the casing 4 are so disposed that the gas cap 5 is properly positioned within the casing 4 so that the outlets 11 and 12 45 of the chambers 6 and 7 will be in alignment with the supply pipes 3.

The circular burner is provided with partitions 13 forming a quarter and a three-quarter section, the quarter section communicating with the chamber 7 and the

three-quarter section with the chamber 6 which enables either or both of the burner sections to be ignited for the purpose hereinafter fully described.

The annular burner 1 is provided with a 60 vertically disposed flange 14 over which is arranged the lower edge of an outer casing 15 which is secured thereto as clearly shown in Fig. 1, and has its upper edge turned down over an annular flange 16 of a ring 16' which is provided with integral flues 17 terminating in a central drum 18. The ring is mounted on an inwardly projecting annular bead 15' formed on the casing 15 adjacent its upper edge and forming means 65 for supporting the parts carried by the ring and to provide a tight joint between the ring and casing. Mounted on the turned-over portion of the outer casing is a foraminated cap 19 having an annular flange 20 70 projecting over the outer casing as clearly shown in Fig. 1.

Mounted on the supply pipes 3 of the burner 1 is a circular metal lining 21 which is spaced from the burner 1 in order to produce an annular air inlet 22 so as to give 80 the burner a free supply of air in order to obtain the proper combustion.

Arranged within the circular lining 21 is an inner casing 23, the upper edge of which 85 is secured to the depending annular flange 24 of a ring 25 which is provided with an annular vertically disposed flange 26 carrying an inner casing section 27, the upper edge of which is secured to an annular 90 flange 28 formed integral with the flue sections 17 as clearly shown in Fig. 1.

The inner and outer casings 15 and 23 form an annular combustion chamber 29 which communicates with the reduced portion of the chamber formed by the casings 15 and 27 which chamber communicates with the flues 17 through which the products of combustion pass into the drum 18 from which they are conveyed by a pipe 30 100 extending downwardly through the central air chamber.

The pipe section 30 has an elbow 31 connected thereto which in turn is connected to a pipe 32 extending through a ring 33 for 105 conveying the products of combustion to a chimney flue in the ordinary manner, and it will be seen by this construction I obtain a down-draft for the products of combustion so that all of the heat units will be 110

absorbed by the central volume of air passing through the stove before they escape to the chimney.

The burner 1 is provided with a plurality of apertures 34 which are drilled obliquely in order to direct the flame against the lining 21 which absorbs the heat so as to throw the same off by radiation. The chambers 6 and 7 are provided with valve controlled fuel supply pipes 35 and 36 in order to allow either or both of the fuel supply pipes to be open, to the fuel gas chambers 6 and 7 provided with outlet openings 11 and 12 through which the fuel passes and is mixed with the air drawn up through the casing 4 so that the proper mixture is delivered to the burner 1 through the supply pipes 3 in order to obtain a perfect combustion, the casing 4 and the gas cap 5 forming a mixer. The outer casing 15 is provided with a door frame 37 closed by a door 38 by means of which the burner can be ignited, and in constructing a stove as herein shown and described the quarter section of the burner is disposed under the door within the combustion chamber so that the same can be ignited which in turn will ignite the three-quarter section of the burner, and by controlling the fuel supply pipes 35 and 36 the quarter section can be used independent of the three-quarter section, or the three quarter section independent of the quarter section, or the entire burner can be ignited and used in order to produce an intense heat. In the operation of the stove as herein shown and described assuming that the burner has been entirely ignited within the combustion chamber 29 the inner and outer casings will soon become thoroughly heated so that the outer casing will throw off heat by radiation, and as the air enters the central air chamber and passes up through the stove it will absorb the heat units from the inner casing and be emitted through the foraminous top so that all of the heat units produced by the burner will be absorbed by the air in order to produce a heating stove which is very economical in use.

If it is desired to only obtain a small amount of heat, by closing the valve in the

supply pipe 35 the quarter section of the burner can be used with good results.

While I have shown and described a stove employing gas as a heating medium I do not wish to limit myself to a gas burner as a vapor burner might be employed without departing from the spirit of my invention.

In the modification shown in Fig. 3 the combustion chamber formed by the inner and outer casing 39 and 40 is provided with an outlet 41 adapted to be connected to a chimney flue 42 in order to allow the products of combustion to escape directly from said combustion chamber and instead of providing a concavo-convexed cap I provide a cap 43 having a flat top 44.

From the foregoing description it will be seen that I have provided a heating stove with an annular combustion chamber having a burner arranged therein divided into sections either or both of which can be ignited, said combustion chamber surrounding the central air chamber through which air is adapted to circulate to be heated.

I claim:

A heating stove comprising a burner ring mounted on legs and provided with radial supply pipes, said burner ring having an annularly disposed flange, an outer casing mounted on said burner ring and secured to said flange, an inner casing mounted on said supply pipes and spaced from said burner ring to provide an annular air inlet, said casings forming an annular combustion chamber, and a central air flue extending from the bottom of said stove to the top thereof, a drum disposed centrally in the upper end of said air flue, pipes extending radially from said drum, and communicating with the upper end of said combustion chamber, and a depending outlet pipe extending downwardly from said drum and having a laterally extending portion passing through said casings.

In testimony whereof I hereunto affix my signature in the presence of two witnesses.

EUGENE ORA DANIELS.
